(57) **CLAIM**

The ornamental design for a drawer cabinet, as shown and described.

DESCRIPTION

FIG. 1 is a top perspective view of the drawer cabinet of the instant invention;

FIG. 2 is a front view thereof;

FIG. 3 is a right side view thereof, the left side view being a mirror image thereof;

FIG. 4 is a top view thereof; and,

FIG. 5 is an environmental view thereof illustrating the drawer cabinet in a stacked arrangement.

The portions of the Figures shown in broken lines are for illustrative purposes only and form no part of the claimed design.
